UNITED STATES PATENT OFFICE

JESSE W. RENO, OF NEW YORK, N. Y.

EXPLOSIVE SHELL.

SPECIFICATION forming part of Letters Patent No. 624,978, dated May 16, 1899.

Application filed May 19, 1898. Serial No. 681,111. (No model.)

To all whom it may concern:

Be it known that I, JESSE W. RENO, a citizen of the United States of America, and a resident of the city, county, and State of New York, have invented certain new and useful Improvements in Shells, of which the following is a specification.

My invention relates to projectiles of the class known as "shells," the object being to provide a projectile of this class which may be fired from a cannon of ordinary construction and which when it strikes the armor of a ship shall be capable of embedding its head in the armor and permitting the main body of the shell, carrying the explosive, to drop at the side of the vessel and explode after it has reached a suitable point below the water-line.

It is customary to provide war vessels with armor consisting usually of thick steel plates, such armor being arranged to protect the vital parts of the vessel above the water-line and extending usually from three to four feet below the water-line. Below the armor the hull of the vessel is formed of comparatively thin steel plates, which are relatively easy to penetrate. It is impossible in the ordinary method of firing a projectile from above the surface of the water to make it reach below the armored protection below the water-line, the reason being that when this is attempted the shell ricochets along the surface of the water.

In the preferred form of my invention, herein shown and described, Figure 1 is a longitudinal section of a shell embodying my invention. Fig. 2 is a transverse sectional view of a war vessel, showing the position of the shells after the vessel has been struck.

Similar characters of reference designate like parts in both of the figures.

1 represents the main body of the shell, in which the explosive is contained.

2 represents the base or closure for the open end of the shell.

3 represents a hole in the base, adapted to receive a detonator or fuse of any appropriate construction.

4 represents the head, which is adapted to penetrate into the armor and is preferably made of hardened steel.

5 represents a flange which is integral with the head 4 and is secured to the main body of the shell 1 by the screws 6 6'.

7 represents a contracted neck joining the head 4 with the flange 5, the purpose of which will be more fully explained hereinafter. 55

8 represents a flexible connection by means of which the main body of the shell is suspended from the head after the shell has struck. This connection, as herein shown, consists of a flat steel ribbon or band preferably made of wrought iron or a low grade of steel. 60

9 represents a thickened end of the ribbon, which is riveted to the swivel-ring 10. 11 represents the other end of the ribbon, which 65 is also thickened and riveted to the connecting-piece 12, the said connecting-piece 12 being rigidly secured to the flange 5 of the head.

The end of the main body portion is turned down to a smaller diameter than that of the 70 outside of the shell for the purpose of forming, in connection with the flange 5, a groove in which the ribbon 8 and ring 10 are received. A groove 13 is also formed in the end of the body portion and is engaged by the pins 14 14, 75 which pins are secured to the ring 10, whereby the ring is prevented from coming off from the body portion, but is free to turn thereon.

A shroud 15, made of copper or other suitable material which is soft relative to the 80 head, surrounds the head 4 and neck 7 and abuts against the shoulder 16, formed by the flange 5. The purpose of the shroud 15 is threefold—namely, to give the forward end of the projectile an exterior form which is best 85 adapted to reduce the air-resistance during the flight of the shell, to reinforce and strengthen the head 4 as it enters the armor-plate, and to form a cushion which shall lessen the shock due to the impact of the projectile 90 against the armor which it strikes.

The screws 6 6' are made of such strength as to hold the head in position during handling and firing. At the same time they are made weak enough so that they may be ruptured by the rebound of the body portion of the shell or sheared off by its rotation. In the ordinary high-power gun shells are given a rotative speed of about two thousand revolutions per minute, so that when the head becomes fixed in the armor-plate the continued rotation of the body portion will sever the screws. 95 100

The purpose of the ring 10 is to permit the

body portion to rotate after it has become detached from the head without causing injury to the ribbon.

The purpose of having the diameter of the neck 7 made slightly less than that of the largest part of the head 4 is to permit the metal surrounding the head to be crowded in, thereby making it more certain to have the head retained in the armor-plate.

10 Having thus described my invention, what I claim is—

1. In a shell, the combination with a detachable head and a main body portion having a circumferential annular groove formed 15 on the end of said body portion adjacent to said head, of a flexible steel ribbon adapted to be coiled in said groove, having one end attached to said head and the other to said body portion.

2. In a shell, the combination with a detachable head and a main body portion having a circumferential annular groove formed on the end adjacent to said detachable head, of the swivel-ring 10, the flexible connection 25 8, adapted to be coiled in said circumferential groove, attached at one end to the swivel-ring 10 and at its other end to the detachable head.

3. The combination with a projectile of a head therefor having a pointed end of conoidal 30 shape, and a neck joining the said pointed portion to a base portion, said neck having a smaller diameter than the largest diameter of said pointed portion.

4. The combination with the body portion 35 of an explosive shell, of a detachable head therefor comprising a base portion and a penetrating portion of hard material and small diameter relative to that of the shell, and a shroud, surrounding said penetrating-head, 40 of softer material.

5. In a shell, the combination with the main body portion adapted to be charged with explosive material, of a detachable head having a hardened penetrating portion of small diameter relative to that of said body portion 45 and an enlarged flange at its rearward end adapted to be secured to the end of the main body portion, and an encircling shroud of

softer material enveloping said penetrating-head.

6. In a shell, the combination with the main body portion adapted to be charged with explosive material, of a penetrating-head of smaller diameter than said main body portion, said head having an enlarged flange to which it is connected by a neck portion of slightly smaller diameter than the largest diameter of said head, and an encircling shroud of softer material enveloping said head and neck portion, having an exterior form adapted to reduce air resistance.

7. In a shell, the combination with the main body portion adapted to carry explosive material, of a penetrating-head of smaller diameter than said main body portion, said penetrating-head having an enlarged flange, means for securing said flange to said body portion, a flexible connection connected at one end to said flange and at the other end to a ring adapted to be swivably connected to the end of said body portion, and an encircling shroud of softer material for the head.

8. In a shell, the combination with a main body portion adapted to receive explosive material, of a detachable head provided with a penetrating portion of smaller diameter than the main body portion, a flexible connection joined at one end to the detachable head and at the other end to the main body portion, and means for cushioning said head as it strikes its target.

9. In a shell, the combination with a detachable head and a main body portion having a circumferential groove formed adjacent to said head, of a ring in said groove swivably connected to said head, a flexible ribbon, having one of its ends attached to said swivel-ring and its other end pivotally joined to a connecting-piece, as 12, said connecting-piece being securely attached to said head.

Signed by me, at New York city, this 18th day of May, 1898.

JESSE W. RENO.
